UNITED STATES PATENT OFFICE

JAMES S. REID, OF CLEVELAND, OHIO, ASSIGNEE, BY MESNE ASSIGNMENTS, TO THE
EATON AXLE & SPRING COMPANY, OF CLEVELAND, OHIO, A CORPORATION OF OHIO

CLOSURE

Application filed October 10, 1927. Serial No. 225,352.

This invention relates to improvements in closures of the type provided with opposed locking fingers for cooperation with opposed cam portions of the device to be closed.

5 The general object of the present invention is the provision of an improved closure of this type which comprises a minimum number of inexpensively formed and readily assembled parts, and in which closure the locking fingers 10 are secured to a part which in turn is positively interlocked with the part to which rotary movement is directly imparted in applying and removing the closure, thereby providing a closure which is exceptionally strong and 15 sturdy; and which interlock is of such character that a vent is provided therethrough for an air chamber of the closure.

Further objects of the invention are in part obvious and in part will appear more in 20 detail hereinafter.

In the drawings which represent one suitable embodiment of the invention, Fig. 1 is a top plan view of the closure; Fig. 2 is a bottom plan view thereof; Fig. 3 is a vertical 25 sectional view thereof on the line 3—3, Fig. 2; Fig. 4 is a vertical sectional view of the closure on the line 4—4, Fig. 2, with the closure applied to the tubular filler neck of a tank; and Figs. 5 and 6 are respectively a top 30 plan view and a vertical sectional view of said filler neck.

The closure illustrated in the drawings includes a one-piece body member which constitutes the inner wall of the closure and 35 includes a central cup-shaped portion 1, 2, and a horizontal flange portion 3 of annular form extending outwardly from the top of the cup-shaped portion. Said cup-shaped portion includes a cylindrical side wall 1 and 40 a circular bottom wall 2 having a centrally disposed depending dome 4 of circular form which provides a recess to receive the substantially circular base portion 5 of the closure locking member. Said locking member 45 is provided with two opposed locking spring fingers 6 extending upwardly and outwardly from said base portion and terminating in directly outwardly extending cam engaging end portions 7 which project 50 through opposed openings 8 in the cylindri-

cal side wall 1 of the body member. While the base portion of said locking member may be secured within the recess of the dome 4 by any suitable means, it is preferably crimped therein, and in the present embodiment of the invention, two opposed side edge portions 9 are crimped about the corresponding side edge portions of the locking member base portion 5, as clearly indicated in Fig. 3. Preferably, and as shown, a circular opening 10 is provided at the center of the depending dome 4 for facilitating the construction of this part of the closure, as will be readily understood.

The closure body member or inner wall is 55 covered by a suitable top member which constitutes the outer wall of the closure and which comprises a circular dome portion 15 and a depending cylindrical skirt portion 16. The horizontal flange portion 3 of the 60 body member or inner wall is secured to the cover member or outer wall at the junction of the dome and skirt portions of the latter, preferably by a crimping operation. In order to positively interlock these parts and thereby prevent relative rotary movement 65 thereof, the horizontal flange portion 3 of the body member is provided with an outwardly extending wedge-shaped projection 18 which is adapted to lie within a correspondingly shaped groove or recess formed by pressing outwardly a portion 19 of the cylindrical skirt portion 16 of the top member. Preferably, and as shown, said pressed out ridge 19 is a continuation of an upwardly 70 pressed out ridge 20 which extends diametrically across the dome portion 15 of the top member, said ridge not only strengthening 75 said dome and skirt portions but also giving 80 them a more ornamental appearance. As indicated in Fig. 2, a clearance 21 is provided between the projection 18 and the skirt ridge portion 19, said clearance being for venting 85 purposes, as will later appear.

In the present embodiment of the invention, 90 an inverted cup-shaped member 23 is positioned within and at substantially the top of the cup-shaped portion 1, 2 of the closure body member, as clearly indicated in 95 Figs. 3 and 4. Said member 23 divides the 100

space within the closure into two air chambers, a lower air chamber 24 within the cup-shaped portion of the closure body member and an upper air chamber 25 within the dome portion 15 of the top member. One or more openings 26 are provided in member 23' for establishing communication between the two air chambers and communication between the upper air chamber and the outside atmosphere is established by the interlock clearance 21, and, if desired, by additional opening or openings 28 in the top flange portion 3 of the body member near the outer edge thereof.

In the present illustration of the invention, the tank 30 or other device to be closed has its filling opening 31 surrounded by an upwardly extending filler neck having a tubular body wall 32. Said wall may be an integral part of the tank or separate therefrom and provided with a laterally extending base flange 33 suitably secured thereto.

At its upper end, said tubular body wall is provided with an inwardly extending, substantially horizontal flange 35 which terminates in a depending flange 36. At two diametrically opposite points, portions of flanges 35 and 36 are cut away to provide two openings or passageways 37 through which the end portions 7 of the closure locking fingers are adapted to be passed, as will later appear. The cutting away of said flanges provides two depending flange portions 36 of substantially semi-circular form and the bottom edges of these flange portions are inclined to provide cams 38 with which the end portions 7 of the closure locking fingers are adapted to cooperate in effecting detachable locking connection of the closure with the filler neck. Recessed dwell portions 39 are provided in the rear end of these cams in which the end portions 7 of the closure locking fingers are adapted to seat when the closure is in fully seated position on the filler neck. Just beyond said dwell portions, the depending flange portions 36 are provided with depending lugs or projections 40 which provide stops for the closure locking fingers during their travel up the cams 38 and insure the seating of said fingers in the dwell portions 39.

The closure is applied to the filler neck in the usual manner of bayonet joint connections, the locking spring fingers of the closure being passed down through the passageways 37 of the filler neck. The closure is then turned in a clockwise direction which causes the fingers thereof to ride up the cams 38 with yielding effect, rotary movement of the closure being continued until said fingers strike the stop portions 40. To remove the closure, it is only necessary to turn it in the reverse direction, whereupon the closure fingers will leave the dwell portions 39 and will ride down the cams 38 to the passageways 37.

The closure can then be removed from the filler neck, the closure fingers being passed up through the passageways 37, as before.

Preferably, the closure is provided with a yielding gasket 45 which is adapted to snugly surround the central cup-shaped portion of the body member and to engage the lower surface of the horizontal flange 3 of said member. While the engagement of the gasket 45 with the cup-shaped portion of the closure body member is usually snug enough to maintain the gasket in proper position, said gasket cannot escape from the closure due to the outwardly extending finger portions 7 therebelow. When the closure is applied to the filler neck, as in Fig. 4, said gasket engages the top flange 35 of the filler neck and effectively seals the opening thereof. Said gasket is not of sufficient width to reach the cylindrical skirt portion 16 of the closure top member, so that any vent opening or openings 28 in the horizontal flange portion 3 of the body member are not covered thereby. However, if desired, the horizontal flange portion 3 of the closure body member and the dome portion 15 of the closure top member may be made of less cross extent, so that the depending skirt portion 16 of said top member will snugly surround the gasket 45 and the closure as a whole will be of substantially the same cross dimension as the filler neck. In this event, the upper air chamber 25 of the closure will be vented to the outside atmosphere through the interlock clearance 21, and, if desired, an opening or openings may also be provided in the dome portion 15 of the closure top member.

The lower air chamber 24 of the closure is vented to the inside of the filler neck and hence to the tank 30 by means of the openings 8 through which the closure locking fingers 6 project. The partition member 32 therefore not only strengthens the closure but also serves as a baffle for openings 8. If the closure is used on the filler neck of an automobile radiator the vent openings for the upper air chamber may be omitted, as will be readily understood.

What I claim is:

1. A closure, comprising a body member having a central cup-shaped portion and an annular top flange portion, said cup-shaped portion being provided with two opposed openings, a locking member mounted within said cup-shaped portion and having opposed resilient locking fingers extending outwardly through said openings, a cover member for said body member comprising a dome-shaped top portion and a depending cylindrical skirt portion, the top flange portion of said body member being secured to said cover member at the junction of the top and skirt portions thereof, and a brace and baffle member positioned in the cup-shaped portion of the body member at substantially the top thereof and

- dividing the space between the cover and body members into two upper and lower air chambers, said brace and baffle member being provided with an opening for establishing communication between said air chambers, said upper air chamber being vented to the atmosphere by an opening in the top flange portion of the body member and the lower air chamber being vented by the openings in the cup-shaped portion of the body member. 70
- 5 2. A closure, comprising a sheet metal body member, locking means carried thereby, and a one-piece sheet metal cover member for said body member having a top portion and a depending cylindrical skirt portion, said cover member being provided with an outwardly pressed hollow strengthening ridge extending across the top portion thereof and down the skirt portion thereof and forming an interior 80
- 10 elongated groove, said body member being provided with a peripheral projection entering the groove in the skirt portion of the cover member, whereby an interlocking connection is provided between said cover and 85
- 15 body members which prevents relative rotary movement thereof. 90
3. A closure, comprising inner and outer wall structures having portions separated to provide an air chamber therebetween, interlocking means between said wall structures for preventing relative rotary movement thereof, and locking means carried by said inner wall structure, said inner wall structure being provided with an opening through 95
- 20 which said air chamber is vented to the interior of the device to which the closure is connected and said interlocking means being provided with a clearance through which said air chamber is vented to the outside atmosphere. 100
4. A closure, comprising inner and outer wall structures having portions separated to provide an air chamber therebetween, one of said wall structures having a projection and the other wall structure having a recess to receive said projection, whereby an interlocking connection is provided between said wall structures which prevents relative rotary movement thereof, and locking means carried by said inner wall structure, said inner wall structure being provided with an opening through which said air chamber is vented to the interior of the device to which the closure is connected and said interlocking projection being so constructed and being so arranged in the recess receiving it that a clearance is provided through which said air chamber is vented to the outside atmosphere. 105
- 45 5. A closure, comprising inner and outer wall structures having portions separated to provide an air chamber therebetween, said inner wall structure having a projection and said outer wall structure having a recess to receive said projection, whereby an interlocking connection is provided between said wall structures which prevents relative rotary movement thereof. 110
- 50 6. A closure, comprising inner and outer wall structures having portions separated to provide an air chamber therebetween, said inner wall structure having a projection and said outer wall structure having a recess to receive said projection, whereby an interlocking connection is provided between said wall structures which prevents relative rotary movement thereof. 115
- 55 7. A closure, comprising inner and outer wall structures having portions separated to provide an air chamber therebetween, said inner wall structure having a projection and said outer wall structure having a recess to receive said projection, whereby an interlocking connection is provided between said wall structures which prevents relative rotary movement thereof. 120
- 60 8. A closure, comprising inner and outer wall structures having portions separated to provide an air chamber therebetween, said inner wall structure having a projection and said outer wall structure having a recess to receive said projection, whereby an interlocking connection is provided between said wall structures which prevents relative rotary movement thereof. 125
- 65 9. A closure, comprising inner and outer wall structures having portions separated to provide an air chamber therebetween, said inner wall structure having a projection and said outer wall structure having a recess to receive said projection, whereby an interlocking connection is provided between said wall structures which prevents relative rotary movement thereof. 130
